COMBINED BUMPER AND GRILLE UNIT FOR AN AUTOMOBILE

Jack E. Kenitz, Detroit, Mich., assignor to Chrysler Corporation, Highland Park, Mich., a corporation of Delaware

Application June 26, 1958, Serial No. 51,549

Term of patent 7 years

(Cl. D14—18)

Fig. 1 is a front view of a combined bumper and grille unit for an automobile embodying my new design;

Fig. 2 is a top plan view thereof;

Fig. 3 is a side elevational view thereof;

Fig. 4 is a sectional view taken on the line 4—4 of Fig. 1;

Fig. 5 is a fragmentary enlarged view of an area designated by the circle numbered 5 in Fig. 1; and

Fig. 6 is a sectional view taken on the line 6—6 of Fig. 1.

I claim:

The ornamental design for a combined bumper and grille unit for an automobile, substantially as shown.
